UNITED STATES PATENT OFFICE.

EDMUND HOFFMAN, OF BROOKLYN, NEW YORK, ASSIGNOR TO AMERICAN CAN COMPANY, OF NEW YORK, N. Y., A CORPORATION OF NEW JERSEY.

DESIGN FOR A POWDER-BOX.

50,973.

Specification for Design. Patented June 26, 1917.

Application filed February 21, 1916. Serial No. 79,788. Term of patent 7 years.

To all whom it may concern:

Be it known that I, EDMUND HOFFMAN, a citizen of the United States, residing at 320 Eighth avenue, Brooklyn, in the county of Kings and State of New York, have invented a new, original, and ornamental Design for a Powder-Box, of which the following is a specification, reference being had to the accompanying drawing forming a part thereof.

In the drawing, Figure 1 is a top plan and Fig. 2 is a side elevation of a powder box showing my new design.

The design is mainly characterized by the peculiar shape of the walls of the box, which converge from a shape which is oval at the bottom, when viewed vertically, to a shape which is circular at the top on a plane at the lower edge of the top of the box.

I claim:

The ornamental design for a powder box, as shown and described.

EDMUND HOFFMAN.
